CLAIM

The ornamental design for a ceiling fan light kit, as shown and described.

DESCRIPTION

FIG. 1 is a bottom perspective view of a ceiling fan light kit showing my new design in the environment of a ceiling fan; FIG. 2 is a top perspective view thereof; FIG. 3 is a top view thereof; FIG. 4 is a bottom view thereof; and, FIG. 5 is a side view thereof.

The broken lines showing a ceiling fan in FIG. 1 illustrate environmental subject matter only and form no part of the claimed design. All other broken lines depict portions of the ceiling fan light kit that form no part of the claimed design.
